UNITED STATES PATENT OFFICE.

DUDLEY GARST, OF WATERLOO, IOWA.

SPREADING DEVICE.

1,396,106.

Specification of Letters Patent.

Patented Nov. 8, 1921.

Application filed October 12, 1920. Serial No. 416,397.

To all whom it may concern:

Be it known that I, DUDLEY GARST, a citizen of the United States of America, and a resident of Waterloo, Black Hawk county, 5 Iowa, have invented certain new and useful Improvements in Spreading Devices, of which the following is a specification.

My invention relates to improvements in spreading devices, particularly to machines 10 for evenly distributing straw, manure and the like, broadcast upon the soil.

An object of my improvements is to combine with the assemblage of delivering and distributing mechanisms, means for assisting 15 in forwarding the load to said mechanisms constantly and evenly without lumps or consolidations, thus insuring proper handling and evacuation of the load.

A further object of my improvements is 20 to associate with the above means resilient hangers or light yieldable pressure elements which may bear with a required reactive power upon the crest of an advancing load directively. A further object of my improvements is to include a suitable removable barrier in advance of the rotatable distributor 25 adapted to keep the materials away therefrom during loading of the rack, to obviate interference and possible breakage.

30 A further object of my improvements is to furnish a wind-shield or hood for the rotatable distributor, to prevent wind scattering of light materials, and confine distribution within proper limits.

35 With the foregoing and other objects in view which will appear as the description proceeds, the invention resides in the combination and arrangement of parts and in the details of construction hereinafter described 40 and claimed, it being understood that changes in the precise embodiment of invention herein disclosed can be made within the scope of what is claimed, without departing from the spirit of the invention.

45 These improvements also are improvements in the device which I have previously patented under Patent No. 1,147,012, of July 20, 1915.

I have accomplished the above objects by 50 the means which is hereinafter described and illustrated in the accompanying drawings. Figures 1 and 2 are elevations of opposite sides of the machine, with parts removed or broken away. Fig. 3 is a rear elevation of 55 the device with the wind shield removed.

Fig. 4 is a detail side elevation of one of the traction-wheels and the means employed to elevate the lower flight of an apron chain above it. Fig. 5 is a perspective view of the reciprocating directing device, and Fig. 6 is 60 an under plan of the same. Fig. 7 is a side elevation of said directing device. Fig. 8 is a detail side elevation of one of the resilient pressure bars, the dotted lines indicating different positions thereof under varying 65 degrees of compression.

Similar numerals of reference denote corresponding parts throughout the several views.

My improved device relates primarily to 70 straw spreaders wherein a rack of large capacity is used. The relatively capacious rack is of skeleton construction, the spaced sideboards 3 being secured on stanchions 4 preferably converging upwardly, the general construction of the rack, with its carrying wheels 6, traction wheels 7 and reach 11 being like that shown in my said patent. Sprocket-rings 8 are mounted on the spokes of said traction wheel. 80

The device contains load moving means consisting of an endless carrier apron. This has endless side sprocket chains 18 of which the upper flight moves rearwardly over the floor of the rack adjacent said stanchions, 85 the opposite chains being connected by cross-bars in a well-known manner, to receive and push along a superposed load. The forward ends of these chains are mounted on idler sprocket wheels 20, while the rear ends of 90 the chains are mounted on sprocket wheels 21 fixed on a positively rotated shaft 22 carrying on one end a driven ratchet-wheel 24.

The numeral 44 denotes a transverse beater-drum of well known construction, 95 whose longitudinal peripheral bars carry staggered radial beater-teeth or pins 45. This drum is fixed upon a rotatable shaft 42 mounted in bearings on the rearmost stanchions 4, above the rear end of said conveyer 100 apron.

The numeral 49 denotes a rotatable shaft mounted below the rear end of the rack, and carries on its opposite extremities like sprocket pinions 50 which carry the rear 105 ends of sprocket chains 52. The lower flights of the chains 52 are positioned immediately above the sprocket rings 8 for occasional engagement therewith. The upper flights of said chains are carried over 110

idlers 19 on the side-beams 12 to support them at a proper elevation, and the forward ends of said chains are carried about idlers 53, the latter being mounted rotatably on the 5 extremities of arms or cranks 54 fixed on the ends of the transverse rock-shaft 66 which is mounted in the hangers 55. Other arms or cranks 65 extend upwardly from said rock-shaft. The rack has a forwardly ex- 10 tending platform 60 upon one side of which is fixed a rack sector 62, and a hand lever 61 is pivoted on the latter and provided with a movable detent for engagement with recesses in the rack sector. A connecting rod 15 64 connects said lever to the upper end of the right hand arm 65. Said lever may be appropriately shifted to rock the shaft 66 to move the idlers 53 up or down to place the lower flights of the chains 52 out of or into 20 engagement with the driving sprocket rings 8 on the traction wheels 7.

I have provided the above described means for applying the lower flights of the chains 52 to a considerable arc of the toothed circumferential periphery of each sprocket-ring 8. Referring to Fig. 1, the numeral 57 denotes a swinging arm mounted on a pintle 59 projected outwardly from a side beam 12, and this arm carries a terminal pintle on 25 which is rotatably mounted an idler 56, the idler being positioned below said chain 52 to occasionally engage and lift the lower flight of the chain when the arm 57 is swung upwardly. Upon the arm 57 near the pintle 30 59 is a projection 58, and a connecting-rod 60 connects this projection terminally with the hand-lever 61, so that the latter when rocked to lift the arm 54 may also rock the arm 57 upwardly, so that both idlers 53 and 35 56 operate to simultaneously lift the chain 52 out of engagement with the sprocket-ring 8. Rocking the hand-lever in an opposite direction will lower the idler 56 out of engagement with said chain, while simultaneously lowering the other idler 53 to engage 40 the chain with a considerable arc of said ring 8. Both chains 52 are supplied with these devices for simultaneous actuations in the engaging and disengaging of the chains. 45

On one end of the transverse shaft 49 is fixed a sprocket wheel 48 which carries a sprocket chain 47 which also engages a sprocket wheel 46 on one end of the beater-drum shaft 42 for rotating the latter. On 50 the opposite extremity of the shaft 42 is fixed a sprocket pinion 43 carrying a sprocket chain 40 which latter engages a sprocket wheel 39 rotatably mounted on a stub-shaft or pintle 41 projecting from the 55 rack. On a spoke of the wheel 39 is a crank-pin 38 on which is pivoted the upper end of a pitman 37, and the lower end of said pitman is pivotally connected at 31 to a slide-body 29, the latter being slidably mounted 60 on a U-shaped arm 23 which is positioned

astride the ratchet-wheel 24 with the ends of its members pivoted to rock on the shaft 22. The extent of play of the slide-body 29 on said U-shaped arm 23 may be adjusted by the following described means. 33 is a 70 hand-lever pivoted at 35 at its lower end and extends upwardly past a rack-bar 34 which it is adapted to releasably adjustably engage by means not shown.

30 and 32 are pivotally end-connected rods, 75 an end of the rod 32 being pivoted to the hand-lever 33, while an end of the rod 30 is pivoted to the pitman 37 and the slide-body 29 on the same pintle 31. A terminally hooked pull-pawl 25 is pivotally mounted on the U-shaped arm 23 to engage teeth of said ratchet-wheel 24 and is yieldingly retained in contact with said teeth by means of a light tension coiled spring 28 connected thereto and to said arm. A guard 80 pawl 26 also engages teeth of said ratchet-wheel, and is pivotally mounted on a stanchion 4 and has an arm to which is connected a light coiled tension spring 27 to retain the pawl in yielding contact with the 85 teeth of the ratchet-wheel. It will be observed that said driving mechanism moves the apron-conveyer 18 rearwardly at regular interrupted intervals, to carry the load toward the beater-drum 44, thus permitting the latter to strip the load efficiently and regularly 90 without clogging.

I have provided a novel and efficient mechanism for acting upon the upper surface of the rear part of the load. The device or 100 director 74 which is in detail shown in Figs. 5 to 7 is a rectangular frame composed of spaced longitudinal bars 74 connected at their ends by cross-beams 79, and the interspace is traversed by a number of spaced 105 parallel longitudinal bars 75 whose ends are secured to said cross-beams. The bars 75 are spaced at 83 below the bars 74 by the interposed ends of the cross-beams, and these interspaces 83 are traversed by a flat bar 77, 110 preferably of metal whose ends 82 project beyond the bars 74, are bent upwardly and orificed for bolts which secure these ends fixedly to the abutting top bars 3 of the rack. The director 74 is reciprocated in a 115 slanting direction only by means of the following described means. Pintles 73 extend oppositely from the rear end of the director and on them are pivoted the rear ends of pitmen 71 whose forward ends are respectively pivoted to a crank-pin 72 on a sprocket-wheel crank 70, and to one end of a crank 96 which is secured to opposite end of shaft 69. The sprocket wheel 68 is mounted on a through-shaft 69 and carries 120 the upper part of a sprocket chain 67. The lower part of this sprocket chain 67 is engaged about the sprocket pinion 46 on the beater drum shaft 42, the latter thus, by means of the above described mechanism, 125 130

- causing lengthwise reciprocation of the director 74. The director is preferably mounted upon the rear part of the rack, inclined downwardly rearwardly, with its rear part 5 spaced above the beater drum 44. Fixed guide-pins 91 extend inwardly from the rack sides at the top into the interspace 83 of the director sides, so that the director is supported on said pins and upon the cross-bar 10 77 in a manner which allows it to be reciprocated in one plane only.
- The numeral 76 denotes a plurality of longitudinally disposed detents arranged in staggered relation along the under faces of 15 the longitudinal bars 75. Each detent has a relatively long sloping under face 76 of a small degree of angularity sloping upwardly forwardly to the bar 75 on which it is mounted, but at the rear having an abrupt 20 angular face 85.
- The numeral 78 denotes a number of like resilient bars whose upper ends are bent rearwardly and fastened upon the cross-bar 77 with the free parts 78 extending downwardly and rearwardly slopingly through 25 the interspaces of the director bars 75. This positions the depending bars 78 above and in advance of the beater drum 44 so that the rearwardly moving load of straw or other 30 material will contact therewith and compressively spring them upwardly to hold them in variously elevated positions of tension as indicated by the dotted lines in Fig. 8. These bars are only usefully oper- 35 able on the last remnant of the load to prevent toppling over and discharge thereof in a large bunch, because the bars then keep this remnant down long enough to allow it to be regularly distributed.
- The numeral 90 denotes a cross-bar, or 40 baffle-plate which may be positioned removably across the rear part of the rack a little in advance of the beater drum teeth 45. Its ends may be removably mounted between 45 side-bars 3 and also between stanchions 4 and blocks 89 secured to said side-bars. This bar 90 may be mounted across the rack as shown before the loading of the latter, and prevents packing of the load tightly about 50 the beater-drum teeth which would seriously impede the latter at starting and might occasion breakage. This bar 90 is removed when the rack has been filled so that the conveyer apron may carry the load back to the beater drum in a loosened condition due to the 55 clearance space thus permitted.
- In Fig. 4 is illustrated means for elevating a part of the lower flight of each conveyer chain 18 above the traction wheel 7 there- 60 under, and consists of an arcuate plate or bar 16 bracketed upon the side-beam 12 under said flight so that the latter may move slidingly thereover. The same figure shows smaller arcuate plates 17 mounted on the 65 end of the cross-beam 2 which serve as guides for said lower flight at or near the ends of the arcuate plate 16, keeping the flight at those places down.
- I have provided a wind-shield or hood 87 at the rear of the rack, which is closed at 70 the sides and rear, and open at the front, top and bottom. This wind-shield is removably supported on the rearmost stanchions 4 by means of U-shaped brackets 88. This shield 75 incloses the beater-drum 44 and has its open upper end immediately below the rear-part of the director 74, while its open lower end is spaced a relatively short distance above the ground. This wind-shield serves to conduct the load as delivered by the beater drum 80 evenly upon the ground.
- The director 74 may have its angularity of slope adjusted by vertically adjusting the position of the pins 91 in the vertical slot 93 of a plate 94 on each side of the rack, and 85 then securing the pins in adjusted positions by nuts 92.
- The sloping detents 76 are purposely made very low so that when the director is reciprocated they will merely scratch the surface 90 of the load when the director is moving rearwardly, and not project far enough into the load to engage it and thrust portions thereof in bunches toward the beater drum. The action of the director is thus effective 95 in imparting a gentle rearward movement to the rear upper part of the load, directing it evenly toward the beater drum.
- Having described my invention, what I claim as new, and desire to secure by Letters Patent, is:
1. In a straw spreader, running-gear, a rack mounted thereon having an open delivery end and relatively high sides, carrying-means movable along the bottom of the rack 105 toward its delivery end, ejecting-means mounted in the lower part of the open delivery end of the rack, supporting-means positioned at the rear top parts of the rack sides, and a reciprocatory rubbing body mounted 110 in said supporting means to reciprocate only in a single plane.
  2. In a straw spreader, running-gear, a rack mounted thereon having an open delivery end and relatively high sides, carrying- 115 means movable along the bottom of the rack toward its delivery end, ejecting-means mounted in the lower part of the open delivery end of the rack, supporting-means positioned at the rear top parts of the rack sides, 120 and a reciprocatory rubbing body mounted adjustably in said supporting means to reciprocate only in a single plane.
  3. In a straw spreader, running-gear, a rack mounted thereon having an open delivery end and relatively high sides, carrying- 125 means movable along the bottom of the rack toward its delivery end, ejecting-means mounted in the lower part of the open delivery end of the rack, supporting-means posi-

tioned at the rear top parts of the rack sides, a reciprocatory rubbing body mounted in said supporting-means to reciprocate only in a single plane, and inclined downwardly 5 rearwardly over said ejecting-means.

4. In a straw spreader, running-gear, a rack mounted thereon having an open delivery end and relatively high sides, carrying-means movable along the bottom of the rack 10 toward its delivery end, ejecting-means mounted in the lower part of the open delivery end of the rack, supporting-means positioned at the rear top parts of the rack sides, a reciprocatory rubbing body mounted 15 in said supporting means to reciprocate only in a single plane, and having numerous relatively short rugations on its under rubbing face.

5. In a straw spreader, running-gear, a

rack mounted thereon having an open delivery end and relatively high sides, carrying-means movable along the bottom of the rack toward its delivery end, ejecting-means mounted in the lower part of the open delivery end of the rack, supporting-means positioned at the rear top parts of the rack sides, a reciprocatory rubbing body having openings mounted in said supporting means to reciprocate only in a single plane, and a plurality of relatively long elastic fingers 30 supported at their upper ends on said supporting-means traversing openings in said reciprocator and directed downwardly slopingly toward and in advance of said ejecting-means.

Signed at Waterloo, Iowa, this 7th day of October, 1920.

DUDLEY GARST.
